UNITED STATES PATENT OFFICE.

PIERRE SYLVAIN GAURIAT, OF PARIS, FRANCE, ASSIGNOR TO PATHÉ CINEMA,
ANCIENS ÉTABLISSEMENTS PATHÉ FRERES, OF PARIS, FRANCE.

MOTION-PICTURE APPARATUS.

Original application filed March 15, 1923, Serial No. 625,238, and in France April 6, 1922. Divided and this application filed February 29, 1924. Serial No. 695,919.

This invention relates to improvements in the device for winding the film upon itself in the receiving chamber of a motion picture apparatus.

5 The present application is a division of the corresponding application No. 625,238 filed on March 15, 1923.

According to the invention, a disc rotatably mounted in a receiving chamber at the 10 lower part of the apparatus has its face inclined with respect to the portion of the film entering the chamber, so as to insure the film to bear upon said disc in order to provide for the regular winding of the film, 15 while a stud carried by said disc makes easier said winding of the film.

According to the present invention the 20 said member provided with an inclined face is constituted by the stud carrying disc or portion of a disc itself.

In the accompanying drawing given by way of example:

Fig. 1 is a side view with partial section of a motion picture apparatus provided with 25 the improved device, according to the invention.

Fig. 2 is a front view of the motion picture apparatus with a cross section of the device according to the invention.

30 The apparatus shown in Figs. 1 and 2 comprises a disc or portion of a disc 50, made of any material, and which carries a stud 50', said disc or portion of a disc is mounted on an axle 46 and rotates in a circular chamber 35 51^a provided in the base of the apparatus and wherein the portion *a* of the film which has been projected is made to enter through the gate 52. Said circular chamber 51 and the disc or portion of a disc 50 are made inclined 40 with regard to the portion of film entering

the chamber through the gate 52. This inclination may, of course, have any suitable value which even may reach 90°, the axis 46 of the disc assuming in the latter case a vertical position. The suitable angle of 45 inclination will depend from the kind of film, size of the apparatus and normal speed of rotation; it will result in each peculiar case from experiments.

Under the direct action of gravity, the 50 edge of the film is caused to bear upon this disc 50. The film when moving downwardly, will meet the disc 50 under a certain angle and the turns of film are formed upon the disc. The rotation of the disc by the 55 handle 26 is obtained by the intermediary of the bevel gears 57 and belt 53.

The stud 50' when rotating around the axle 46 bears constantly upon the inner turn 60 of the film and drives in its motion the turns 65 of film already formed in order to make easier the winding of new turns.

Having now described my invention, what I claim as new and desire to secure by Letters Patent is:

65 In a motion picture apparatus a device for winding the film upon itself provided in a receiving chamber for the film at the lower part of the apparatus and into which the gate for the film is adapted to open comprising: a disc rotatably mounted in said chamber, the face of said disc being inclined with respect to the portion of film entering the chamber, means for rotating said disc and a stud carried by said disc driving the turns of 70 film already formed upon the disc and making easier the winding of new turns. 75

In testimony whereof I have signed my name to this specification.

PIERRE SYLVAIN GAURIAT.
